(57) **CLAIM**

The ornamental design for a monitoring device with sensors for monitoring a livestock facility and/or livestock animals in a livestock facility, as shown and described.

DESCRIPTION

FIG. 1 is a front, left, bottom perspective view of a monitoring device with sensors for monitoring a livestock facility and/or livestock animals in a livestock facility showing the new design;

FIG. 2 is a rear view thereof;

FIG. 3 is a front view thereof;

FIG. 4 is a right side view thereof;

FIG. 5 is left side view thereof;

FIG. 6 is a bottom view thereof; and,

FIG. 7 is a top view thereof.
